UNITED STATES PATENT OFFICE

CLARENCE WILLIAM BRAWLEY, OF BROOKLYN, NEW YORK

SUPPORTING FOOT

Application filed February 18, 1930. Serial No. 429,344.

My invention relates to supporting feet, of the general type used for supporting a light and delicate machine as the same rests upon a desk or table.

More particularly stated, I seek to produce a supporting foot suitable for general use in the relation just mentioned, but specifically adapted for supporting a typing machine.

In this connection it may be stated that a supporting foot for a typing machine or analogous mechanism should be so constructed and arranged as to ameliorate as far as practicable the effects of incessant pounding of the human fingers upon the keyboard of the machine, and also to take up any lost motion as between the frame of the machine and the desk or table upon which it is supported, and further to provide against scratching or other disfigurement of the desk top or the like upon which the machine may be placed.

I endeavor to obtain the advantages just mentioned, by means of a supporting foot of such form as to be cheap to manufacture, reliable in action, easily removed and replaced, and composed of parts readily standardized and in every way suitable for quantity production, and adapted for use as separate feet for a wide range of different articles including not only typing and like machines but other articles for instance telephones, desk trays and boxes of various kinds, and radio cabinets etc.

I endeavor further to provide a supporting foot which may if desired be made up in part of a member which extends common to a multiple of feet, said member for instance being suitable to constitute the bottom wall 40 of a cabinet or box and the foot structures being formed thereon at spaced points suitable for properly supporting the cabinet or box.

Other objects and aims of the invention, more or less specific than those referred to above, will be in part obvious and in part pointed out in the course of the following description of the elements, combinations, arrangements of parts and applications of principles constituting the invention; and

the scope of protection contemplated will be indicated in the appended claims.

In the accompanying drawing which is to be taken as a part of this specification, and in which I have shown merely a preferred form of embodiment of the invention:

Figure 1 is a substantially vertical section through one form of my improved supporting foot, and shows the same as mounted upon a typing machine frame.

Figure 2 is a substantially central section through another form of supporting foot made in accordance with my invention, but somewhat simpler than the form shown in Figure 1.

Figure 3 is a perspective view of a sheet metal plate having a plurality of foot structures provided thereon, and

Fig. 4 is a sectional view taken substantially upon the plane of line VI—VI of Figure 5 and showing the plate as it would appear in use forming the bottom wall of a radio cabinet.

A portion of the frame of a typing machine is shown at 5, and is provided with a base member 6 integral therewith, this base member having a threaded opening 7.

A screw 8 is fitted into the threaded opening 7, and is thus detachably carried by the base member 6. This screw is provided with a convex head 9, which has a slot 10, to facilitate its engagement by an ordinary screw driver.

A metallic eyelet is shown at 11 and is provided with a pair of annular flanges 12, 13, integral with it and each of substantially mushroom form.

The eyelet 11 extends through a circular washer 14 made of soft and resilient material, preferably felt, and provided with a central opening 15.

The washer 14 is sandwiched between an outer metallic shell 16 and an inner metallic shell 17, each shell having the proximate form of a dome, the outer shell 16 having a longer cross diameter than the inner shell 17.

By virtue of the dome-like form of each of the two shells 16, 17, the felt washer 14 is given a general cup-like form. The felt washer is provided with an annular portion

18 which is substantially angular in cross section at its lower edge, as may be understood from Figure 1.

The weight of the frame 5 and part carried 5 thereby rests directly upon the annular edge 18, which in practice flattens out a little, to fit upon a table or desk.

In the form shown in Figure 2 the felt washer 14 and the outer dome 16 each have a 10 form like that shown in Figure 1 and above described.

However, the inner dome shown in Figure 2 has the form indicated at 19 in that figure, and is provided with a neck portion integral 15 with it and terminating in an annular flange 21. The annular flange 21 extends slightly over and engages an annular portion 22 of the outer dome 16. Thus the neck portion 20 serves essentially as an eyelet, in much the 25 same manner as the eyelet 11 above described with reference to Figure 1. The chief difference between the form of my device shown in Figure 1 and the form shown in Figure 2 is, that in Figure 2 there are only two metallic members connected permanently with the washer 14, whereas in Figure 1 there are three metallic members so connected.

I have found in practice that each form of my invention is remarkably efficient, in the 30 relation here contemplated.

By the use of my improved supporting foot the weight of the supporting frame and mechanism carried thereby is distributed 35 equally, or substantially so, as between the several feet employed, of which there are usually four.

The washer 14 is preferably formed originally as a simple flat disk of sheet felt, with a hole at its centre, and it is given the efficient 40 cup or dome-like shape, as shown, by reason of the fact that it is clamped between two opposing cupped or dome-like members. This disposes the annular edge portion of the disk projecting downwardly at an out- 45 flaring angle and condenses and ruffles said edge portion so that it constitutes a desirably firm cushion for engagement with a polished table top or the like.

Because of the softness and resilience of 50 the washer 14, due to the material of which it is made and the manner in which it is formed up, there is little or no lost motion as between the supporting feet and the desk or table upon which the same may rest. Since the annular edge 18 flattens out in consequence of the weight resting upon it, the supporting foot is to some extent automatically formed or shaped to rest upon the supporting surface which it engages.

Where the mechanism supported is subjected to incessant pounding, as by the action of human fingers upon a keyboard, the jar and shock is greatly ameliorated, both as to 65 the fingers and the machine, by the use of

my device. The machine is also protected from extrinsic vibrations.

In each form of my invention the structure is relatively simple. The various parts may be readily standardized and adapted for 70 quantity production.

In the form of my device appearing in Figures 5 and 6 it is contemplated that the outer shell member as 34 thereof, corresponding with the shell 16 of Figures 1 and 2, shall be 75 formed as a dome-like projection pressed into a piece of sheet metal as 35 which has not only one such projection pressed therein but any desired number of projections, the piece of sheet metal being suitably extensive so as 80 to be adapted to serve for instance as the bottom wall of a radio cabinet or the like, and the projections being stamped into said sheet for instance adjacent the four corners thereof, as clearly illustrated in Figure 5. 85 A felt washer 14 is fitted into the dome-like cavity provided by each of the projections and is held in its dome-like form by an inner shell and separate eyelet as in Figure 1, or by a combined inner shell and eyelet as in 90 Figure 2. As illustrated the structure corresponds with that shown in Figure 2, and while the plate 35 may be attached to the bottom of the radio cabinet or the like, as 95 36, by any appropriate means it is contemplated that screws or rivets extending through the centres of the foot structures may continue into engagement with portions of the cabinet for this purpose.

In instances where the cabinet contains 100 some element, as for example the so-called chassis as 37 of a radio set, the screws may engage such chassis to serve the double purpose of clamping the chassis against suitable stops as 38 within the cabinet and at the same 105 time clamping the plate 35, with its improved cupped feet, in position as the bottom of the cabinet.

As many changes could be made in this construction without departing from the 110 scope of the invention as defined in the following claims, it is intended that all matter contained in the above description, or shown in the accompanying drawing, shall be interpreted as illustrative only and not in a limiting sense.

Having thus described my invention, what I claim as new and desire to secure by Letters Patent is:—

1. A device of the class described comprising a sheet metal member having a cup-shaped depression formed at one surface thereof and having an opening therethrough centrally of said depression, a normally flat disc of felt having a central opening therethrough mating the opening of said depression, a second sheet metal member of a size to be received within the depression of the first sheet metal member and having a central opening therethrough and having a 120 125 130

- sleeve connected therewith continuing from said opening extending through the mating openings of the felt and of the first sheet metal member and having engagement with the first sheet metal member to hold the two sheet metal members connected together and to clamp the felt disc in cup-shape within the depression of the first sheet metal member, the marginal portions of the felt disc projecting beyond the outer margin of the depression of said first sheet metal member, and the opening through the second sheet metal member and through the sleeve providing means to receive an attaching element by which the whole may be connected with an article to be supported.
2. A device of the class described comprising a sheet metal member having a cup-shaped depression formed at one surface thereof and having an opening therethrough centrally of said depression, a member of felt having a central opening mating the opening of said depression, a second sheet metal member of a size to be received within the depression of the first sheet metal member and having a central opening therethrough, said second sheet metal member being formed with an integral sleeve continuing from said opening and extending through the mating openings of the felt and first sheet metal member and having its end flanged over upon the surface of the first sheet metal member to hold the two sheet metal members connected together and to clamp the felt member into the depression of the first sheet metal member, the marginal portions of the felt member projecting beyond the outer margin of the depression of the first sheet metal member, and the opening through the second sheet metal member and through the sleeve providing means to receive an attaching element by which the whole may be connected with an article to be supported.
3. A device of the class described comprising a sheet metal member having a cup-shaped depression formed at one surface thereof and having an opening therethrough centrally of said depression, a member of felt having a central opening mating the opening of said depression, a second sheet metal member of a size to be received within the depression of the first sheet metal member and having a central opening therethrough also mating the opening of said depression, one of said sheet metal members being formed with an integral sleeve continuing from its central opening and extending through the mating openings of the felt and of the other sheet metal member and being flanged over upon the surface of said other sheet metal member to hold the two sheet metal members connected together and to clamp the felt member within said depression, the marginal portions of the felt member projecting beyond the outer margin of said depression,

and the openings through said sheet metal members and through the sleeve providing means to receive the attaching element by which the whole may be connected with an article to be supported.

4. A supporting foot comprising a circular washer made of soft and resilient material and provided with an opening, an outer metallic shell and an inner metallic shell engaging opposite faces of said washer and each provided with an opening, and an eyelet forming part extending through said washer and being connected with said inner and outer shells to hold all of said parts assembled adapted to receive fastening means therethrough.

5. A supporting foot comprising a circular washer, made of soft and resilient material and provided centrally with an opening, an outer metallic shell and an inner metallic shell engaging opposite faces of said washer and each provided with an opening, an eyelet extending through said washer and through said outer shell and said inner shell, and a screw extending through said eyelet.

6. A supporting foot comprising a substantially circular normally flat washer made of soft and resilient material and provided with an opening, an outer metallic shell engaging one face of said washer and having the proximate form of a cup, a similarly shaped inner shell engaging the opposite face of said washer, the two cup-shaped shells facing in the same direction, and said inner shell being provided with a neck portion integral therewith and extending through the opening in said washer and engaging said outer shell serving to hold the shells connected to clamp the washer into cup-shape between the shells, the annular marginal portions of the washer projecting beyond the margin of the shells.

In testimony whereof I affix my signature.
CLARENCE WILLIAM BRAWLEY.
